UNITED STATES PATENT OFFICE.

RAYMOND D. EMERY, OF WINCHESTER, MASSACHUSETTS, ASSIGNOR TO WILLIAM M. WHITNEY, OF WINCHESTER, MASSACHUSETTS.

PROFILING-JIG.

1,275,160.

Specification of Letters Patent. Patented Aug. 6, 1918.

Application filed November 20, 1916. Serial No. 132,347.

To all whom it may concern:

Be it known that I, RAYMOND D. EMERY, a citizen of the United States, residing at Winchendon, county of Worcester, and State of Massachusetts, have invented an Improvement in Profiling-Jigs, of which the following description, in connection with the accompanying drawings, is a specification, like characters on the drawings representing like parts.

The invention to be hereinafter described relates to wood-working and other machines, and among other objects, provides simple and effective means for controlling the relation of the work to the tool operating thereon.

The character of the invention may be best understood by reference to the following description of an embodiment thereof, shown in the accompanying drawings, wherein:

Figure 1 is a rear perspective view showing a portion of a wood-working machine and a work holder therefor, embodying the present invention;

Fig. 2 is a front perspective view of the machine and holder shown in Fig. 1;

Fig. 3, on a reduced scale, is a vertical transverse section through parts shown in Figs. 1 and 2; and

Figs. 4 and 5 show illustrative articles which may be shaped by the machine.

Referring to the drawings: 1 designates a portion of a standard supporting a table 3, provided with a cutter tool 5 mounted on a shaft projecting down through an opening in said table and driven by a pulley (not shown) and a belt 7 in the usual manner.

A guide member, in the present instance of the invention, in the form of a bar 9 is fixed by a clamp 11 or other appropriate securing means onto said table, and may have an aperture 13 therein to accommodate the cutter tool shaft. Preferably, the front edge of said bar is elevated somewhat above the table by a strip 15 beneath the same, and projecting out beyond the said edge to present a ledge for a purpose to be hereinafter described.

A second guide member is provided, in the present instance of the invention, in the form of an arm 17 above said guide bar. This arm has a front, rounded end and a rear end adjustably secured to an angle

bracket 19 by a hand screw 21 entered through an elongated slot in said arm, and threaded into the upper leg of said bracket. The lower leg of said bracket is adjustably secured to an upright 21 by a bolt 23 entered through an elongated slot in said upright and threaded into the lower leg of said bracket. The upright may be bolted to the top of said table adjacent said cutter tool. From the construction described, it will be noted that the arm 17 may be readily adjusted horizontally and vertically, as desired.

Next will be described a work holder for controlling the relation of the work to the tool. In the present instance of the invention, this holder is in the form of a frame 70 which may be constructed and arranged to receive work of different shapes and sizes, as required. The illustrative frame shown herein comprises a base plate 25 and ends 27 secured thereto, and adapted to receive the work between them, herein in the form of a post having square ends and a rounded reversely-curved portion between said ends.

The stock may be secured to said frame by any suitable means. Herein, it is shown as 80 clamped at its ends against shoulders 31 in blocks 33 by hooks 35 having ends projecting through and slidable in grooves 37 in said blocks. These hooks have shanks projecting through long bores in said blocks and 85 on their outer ends are threaded butterfly nuts 39. When these nuts are tightened, they will act on the hooks and draw the square ends of the stock securely against said shoulders.

The blocks may be adjusted relatively to the ends of the frame and be secured by bolts 41 entered through bores in said ends and elongated slots in said blocks. These bolts may also pass through cleats 43 to distribute 100 their pressure to said blocks and ends. To further contribute to the positioning of the stock, feet 45 may be provided adapted to rest against the stock intermediate the ends of the latter. These feet may be adjustably 105 mounted on the base plate 25 of the frame, and be secured in different positions of adjustment by butterfly nuts 47 on screws 49 projecting up through slots in said feet.

To determine the curve or other form to 105 be given to the stock, the frame may be pro-

vided with suitable pattern means. In the present instance of the invention, this means is in the form of a plate 51 having an edge 53 curved to conform to the contour to be given the stock. To permit the pattern plate to be readily removed and pattern plates of other form to be applied to the frame, said plate may be detachably secured to the frame by butterfly nuts 55 10 threaded on screws 57 projecting out from cleats 59, Fig. 2, beneath said plate adjacent the ends of said frame. These cleats may be adjustably secured to said ends by bolts 61 projecting through selected holes of the series of holes in said cleats and through elongated slots 63 in said ends.

The opposed edges of the guide bar 9 and the frame base plate 25 may be beveled as shown in Fig. 3, to facilitate the rocking of 20 the frame relative to the tool, as more fully hereinafter described.

An elbow block 65 may be secured to one of the ends of the base plate 25 projecting beyond one of the ends 27 of the frame to 25 limit the rocking movement thereof.

In use, the work to be shaped is clamped into the holder and then the latter is grasped and placed on the table with the rear edge of the base plate resting on the ledge and 30 abutting against the front edge of the guide bar. The holder is then given a rearward rocking movement to cause the curved edge of the pattern plate to engage the rounded edge of the guide arm. The holder is then 35 slid along said ledge and the bar, and in the course of this movement, the holder will be automatically rocked on said ledge as a fulcrum to vary the distance of the work from the axis of the tool and thereby vary 40 the depth of cut made by the tool in the work.

The plate 51 is shown herein merely to illustrate one form of pattern which may be used. Appropriate pattern plates may 45 be used for forming the stock with the contour shown in the article appearing in Fig. 4, or to produce the rifle stock shown in Fig. 5, or other shapes, as desired.

It will be understood that while the invention is described herein more particularly with reference to a wood-working machine, it is applicable to other machines for operating on other materials.

The invention is not limited to the specific 55 details illustrated herein, but extensive de-

viations may be made therefrom without departing from the spirit and scope of the claims.

What is claimed is:—

1. A wood working machine, comprising 60 in combination, a supporting table, a rotary cutter mounted above said table, a right line guide member mounted on said table adjacent said cutter, a standard mounted on said table, a guide element on said standard above said guide member, a separate work carrier having a portion to slide along and rock about said right line guide member, means to secure the work to the carrier, and a pattern mounted on said carrier in predetermined relation to the work and presenting an edge to slide along said guide element as said carrier portion slides along and rocks about said guide member, that the cutter may give the work a form determined 75 by the shape of said pattern.

2. A wood working machine, comprising 80 in combination, a supporting table, a rotary cutter mounted above said table, a guide member mounted on said table, a guide element mounted on said table above said guide member, a separate work carrier for sliding and rocking engagement with said guide member, means to secure the work on said carrier, a pattern having an edge for engagement with said element, and means to secure said pattern to said carrier in predetermined relation to the work, that the work may receive a form determined by the 85 relation of the pattern to the work.

3. A wood working machine, comprising 90 in combination, a supporting table, a rotary cutter mounted above said table with a substantially vertical axis, a work carrier comprising a base, end members secured to said base for receiving the work between them, means to secure the work on said carrier, a pattern secured to said end members in predetermined relation to the work and having a longitudinal edge shaped according to the 95 form to be given the work, means to guide said base in a rectilinear direction as it is fed relatively to said cutter, and a fixed element to engage said pattern edge and cause said carrier base to rock on said guide as a 100 fulcrum as the carrier is fed relatively to the cutter.

In testimony whereof, I have signed my name to this specification.

RAYMOND D. EMERY.
